CLAIM

The ornamental design for a combined tube and cap, as shown and described.

DESCRIPTION

FIG. 1 is a top view of a combined tube and cap showing our new design;

FIG. 2 is a front view thereof;

FIG. 3 is a back view thereof; and,

FIG. 4 is a side view thereof.

The figures show a combined tube and cap useful for a cream or ointment. A bottom view is not shown and has no ornamental features.
